UNITED STATES PATENT OFFICE.

ALBERT R. THOMPSON, OF INDIANAPOLIS, INDIANA, ASSIGNOR OF TWO-THIRDS TO CLARENCE M. ZENER AND JOHN WOCHER, OF SAME PLACE.

AUTOMATIC FIRE-ALARM.

SPECIFICATION forming part of Letters Patent No. 665,040, dated January 1, 1901.

Application filed September 22, 1899. Serial No. 731,266. (No model.)

To all whom it may concern:

Be it known that I, ALBERT R. THOMPSON, a citizen of the United States, residing at Indianapolis, in the county of Marion and State 5 of Indiana, have invented a new and useful Automatic Fire-Alarm, of which the following is a specification.

My invention relates to an improvement in automatic fire-alarms.

One object of my invention is to produce a 10 cheap and effective thermostat which may be used in combination with either a closed or open circuit, and a further object of my invention is to provide a simple alarm and register system combining both closed and open circuits.

The accompanying drawings illustrate my invention.

Figure 1 is a perspective view of the thermostat. Fig. 2 is a central vertical section thereof. Fig. 3 is a section at right angles to Fig. 2. Fig. 4 is a bottom plan view thereof. Fig. 5 is a diagrammatic view of an alarm and register system combining both open and closed circuits provided with my improved thermostat.

In the drawings, 6 indicates a terminal having formed at its upper end a flange 6'. The other terminal 7 is arranged alongside of terminal 6, a suitable distance therefrom, and is provided with a flange 8 at its upper end. Terminal 7 is provided at its upper end with a box-like inclosure 9, which extends toward terminal 6, and the two terminals are insulated from each other by a suitable insulating-block 10. Extending across and within inclosure 9 is an insulating-pin 11, which is provided at each end with an enlarged head, thus forming a pair of shoulders 12. Formed 35 in the upper end of each terminal 6 and 7 is a recess 13, having a tongue 14 bent down from one side thereof partially across the recess, so that wire 15 may be passed around the end of and beneath said tongue. After 40 the wire has been placed within the recess it is soldered in position, and the recess is then filled with any suitable waterproof insulating material 16.

17 indicates a piece of spring metal, which 45 is doubled upon itself and of such form that

the doubled end may be passed into the inclosure 9 and pin 12 passed through the bight thereof, the spring lying between the shoulders 12, and thus being insulated from the two terminals. The ends of spring 17 are 55 normally held out of engagement with terminals 6 and 7 by a small portion of easily-fusible solder 18, as shown.

Secured to the ends of spring 17 are two insulating-blocks 19 and 20, to which are secured terminals 21 and 22, respectively, said terminals being of such form that with the ends of spring 17 normally held together by solder 18 the ends of terminals 21 and 22 will be in engagement with each other. Terminals 21 and 22 are each provided with a recess 23, into which wire 24 may be passed and soldered in position in any suitable manner, preferably such as that just described.

It will be readily understood, of course, 70 that any desirable means of attachment of the wires to the terminals may be used. In the construction described wires 15 form a part of an open circuit, terminals 6 and 7 being connected in parallel, while terminals 21 75 and 22 are arranged for closed-circuit work on wires 24 and are to be connected in series, as shown.

In practice I provide a central station or indicator-box 25, provided with the usual annunciator system, as shown. Mounted in box 25 is a suitable clockwork 26, provided with a rotatable shaft upon which are secured two heads 27 and 28, which are provided with projecting teeth adapted to engage the corresponding terminals 29 and 30, which terminals are insulated from each other and from the clockwork. A suitable brake, such as arm 31, is provided to normally prevent the operation of the clockwork, and this arm is 85 held in its normal position by means of a pin or roller 32, carried by a pivoted arm 33. Arm 33 is provided with a metallic bar 34, which lies opposite an electromagnet 35, and is also provided with a similar bar 36, which 90 lies opposite magnet 37. A spring 38 is connected to the other end of arm 33 for a purpose which will be made to appear. Suitably connected to the electromagnet 35 are the wires 15 of the open circuit, which wires are also 100

connected in parallel, as already described, to the terminals 6 and 7 of a series of thermostats such as those already described.

It will be readily understood that any desired number of circuits 15 may be used, all leading to magnet 35 and properly connected from that point to the annunciator. As shown, magnet 35 forms a part of the open circuit 15 and upon rise of temperature of the medium surrounding any one of the thermostats forming part of circuits 15 the solder 18 will be melted and the ends of spring 17 fly out into engagement with terminals 6 and 7, thus closing the circuit and causing bar 34 to be drawn toward the magnet, so as to withdraw pin 32 from engagement with arm 31, and thus release the clockwork and allow head 27 to be revolved. The revolution of the shaft brings head 28, which is normally out of engagement with terminal 29, into engagement with said terminal, thus intermittently closing and opening the open alarm-circuit. Head 36 is normally held in engagement with the closed-circuit magnet 37 against the action of spring 38. The wires 24 of said circuit are connected to the terminals 21 and 22 of the series of thermostats already described. Under the circumstances when solder 18 is melted the ends of spring 17 are thrown out, thus separating terminals 21 and 22 and breaking the closed circuit 24. By this means the engagement between magnet 37 and head 36 is released, the spring 38 then withdrawing pin 32 from engagement with arm 31 and allowing head 28 to be rotated beneath terminal 30, so as to intermittently break and close the closed circuit, and thus send an alarm through the closed alarm and register circuit.

In order that an alarm may be sent in by hand from the annunciator-station, I connect to arm 33 a link 41 and lever 42, which lever is brought down in the usual manner opposite a glass panel, so that by pulling down the lever 42 the clockwork may be released. By using both the closed and open circuits in the same system the possibility of failure to operate because of defective circuits or defective batteries is very materially lessened, and the thermostat being constructed as it is may be readily used as a part of either the closed or open circuit, or both. Leading from the frame of clockwork 26 is a wire 43, which is common to both the closed and open circuits mentioned, and leading from the end of the said wire 43 are two wires 44 and 45. Wire 44 is connected to one terminal of the primary coil of an ordinary closed relay 46, and the circuit through said coil is completed by wire 47, battery 48, and wire 49, said wire 49 being connected to terminal 30 of the clockwork. A local open circuit 50 is connected to the secondary terminals of the closed relay 46 and to one pair of terminals of suitable pen-register 51, as shown in Fig. 5, said pen-register being of the form ordinarily used in systems of this character. Wire 45 is con-

nected to one terminal of the primary coil of an open relay 53, and this circuit is completed by wire 54, connected to the other terminal 70 of said coil, battery 55, grounded wire 56, and grounded wire 57, which leads to the terminal 29 of the clockwork. Connected to the terminals of the secondary coil of the open relay 53 is a local circuit 58, which is also connected to one set of terminals of the pen-register 51. The pen-register is of the usual form, having energizing-coils, which of course form a part of the respective circuits 50 and 58. A gong 52 forms a part of the circuit 58, 80 and a gong 60 forms a part of the circuit 43, 44, 47, 48, and 49, said gongs being connected with the circuit in the usual manner, the coils thereof forming a part of the said circuits. In the operation when the mechanism 85 of the box 25 has been operated so as to release clockwork 26 heads 27 28 will be revolved, said revolution intermittently breaking and making the closed circuit of which the closed relay forms a part, and this alternate breaking and making of this circuit alternately makes and breaks circuit 50, so as to operate pen-register 51 in the usual manner. At the same time the revolution of head 27 alternately makes and breaks the open 90 circuit of which the open relay forms a part, and said alternate making and breaking alternately makes and breaks circuit 58, which also causes an operation of the pen-register. It is to be understood that the pen-register 100 is of that form in which there are duplicate pens, each of which operates independently of the other. By this system of connections the liability of error or failure to work is decreased, because it is practically certain that 105 one or the other of the closed and open circuits will be in condition to operate.

I claim as my invention—

1. In a fire-alarm, a thermostat consisting of a pair of terminals, a pair of spring-arms 110 mounted between and insulated from said terminals, and a fusible connection for normally holding said spring-arms out of simultaneous engagement with said terminals.
2. In a fire-alarm, a thermostat consisting 115 of a pair of terminals, a doubled piece of spring metal mounted between said terminals and insulated therefrom, and fusible means for normally holding the ends of said spring out of simultaneous engagement with said 120 terminals.
3. In a fire-alarm, a thermostat consisting 125 of a pair of terminals arranged to form a part of an open circuit, a pin mounted between and insulated from said terminals, a pair of spring-conductors electrically connected and mounted upon said pin so as to be insulated from said terminals, a fusible connection between said spring-conductors so as to normally hold them out of simultaneous engagement with said terminals, and a pair of terminals carried one by each of said spring-arms and insulated therefrom, the arrangement being such that said terminals are nor- 130

5 mally held in engagement with each other by means of said fusible connection.

4. In a fire-alarm, a thermostat consisting of a pair of terminals arranged to form a part 5 of an open circuit, a pin mounted between and insulated from said terminals, a doubled spring-conductor pivoted at its bight upon said pin, a fusible connection carried by said spring-conductor so as to hold its ends from 10 simultaneous engagement with said terminals, and a pair of terminals carried by the arms of said spring-conductor and insulated therefrom, the arrangement being such that said terminals are held in engagement with 15 each other by means of said fusible connection.

5. In a fire-alarm, a thermostat consisting of a pair of insulated terminals, a box-like enclosure formed on one terminal, an insulating-pin passing through said enclosure, a doubled spring pivoted at its bight on said pin and lying between said terminals, and a fusible connection between the ends of said spring to normally hold said ends out of 20 simultaneous engagement with said terminals.

6. In a fire-alarm, a thermostat consisting of a pair of insulated terminals arranged to form part of an open circuit, a box-like in- 25 closure formed on one terminal, an insulating-pin passing through said enclosure, a doubled spring pivoted at its bight on said pin and lying between said terminals, a fusible connection between the ends of said spring to normally hold said ends out of simultaneous 30 engagement with said terminals, and a second pair of terminals carried by the ends of said spring and insulated therefrom, said terminals being arranged to form part of a closed circuit and to engage each other when 35 the ends of the spring are held together by the fusible connection.

7. In a fire-alarm, a thermostat consisting of a pair of spring-arms, a pair of terminals carried one by each arm and insulated therefrom, and a fusible connection between said arms so as to normally hold said terminals in engagement with each other.

8. In a fire-alarm, a thermostat, consisting of a single piece of spring material doubled 45 upon itself, a pair of terminals carried one by each of the ends of said spring, and a fusible connection between the adjacent portions of said spring whereby said terminals are normally held in engagement with each other so as to form a part of a closed circuit.

55 9. In a fire-alarm, the combination with an

automatic fire-alarm transmitter, of a pair of electromagnets, one forming a part of a closed circuit and the other forming a part of an open circuit, an arm arranged in position to 60 be operated upon by both of said magnets and adapted to normally prevent the operation of the automatic alarm-transmitter, a closed circuit, an open circuit, and a series of thermostats, each provided with a pair of 65 terminals which terminals are connected to the open circuit, a second pair of terminals which terminals form a part of the closed circuit, and a fusible means for normally holding the second pair of terminals in engagement with each other and for normally maintaining the first pair of terminals out of electrical connection.

10. In a fire-alarm, the combination with an automatic fire-alarm transmitter, of a pair 75 of electromagnets, one forming part of an open circuit, and the other forming part of a closed circuit, an arm arranged in position to be operated upon by both of said magnets and adapted to normally prevent the operation of the automatic alarm-transmitter, a closed circuit, an open circuit, and a series of thermostats, each provided with a pair of 80 terminals which terminals are connected to the open circuit, a piece of doubled spring 85 metal mounted between and insulated from said terminals, a fusible connection normally holding the ends of said spring from simultaneous engagement with said terminals, and a pair of terminals forming part of said closed 90 circuit and being held normally in engagement with each other by said fusible connection.

11. An electrical connection consisting of a suitable terminal or body, a recess formed 95 therein, a tongue formed integral with said terminal and adjacent said recess, and adapted to be thrown down so as to extend partially across the mouth of said recess so that a wire may be slipped around the end of and beneath 100 said tongue into the recess.

12. An electrical connection consisting of a suitable terminal or body, a recess formed therein, and a tongue extending partially 105 across the mouth of said recess so that a wire may be slipped around the end of and beneath said tongue into the recess.

ALBERT R. THOMPSON.
